UNITED STATES PATENT OFFICE.

WILLIAM H. WINSLOW, OF CHICAGO, ILLINOIS, ASSIGNOR TO THE LUXFER PRISM PATENTS COMPANY, OF WEST VIRGINIA.

PRISM-PLATE.

SPECIFICATION forming part of Letters Patent No. 595,277, dated December 7, 1897.

Application filed December 14, 1896. Serial No. 615,669. (No model.)

To all whom it may concern:

Be it known that I, WILLIAM H. WINSLOW, a citizen of the United States, residing at Chicago, in the county of Cook and State of Illinois, have invented certain Improvements in Prism-Plates, of which the following is a specification.

My invention relates to the production of prism-plates such as are used in connection with or instead of window-glass where the complete plate is made up of a series of sections of tile, as in the case of stained glass, prismatic glass, and the like, and has for its object to provide suitable means for so framing up such sections and a complete glass so built up or framed.

My invention is illustrated in the accompanying drawings, wherein—

Figure 1 is a plan view of the working table with a sheet of glass partly built up. Fig. 2 is a plan view of a finished sheet of glass, the smooth side up. Fig. 3 is a similar view with the prismatic side of the glass up. Fig. 4 is a section through a portion of the same. Fig. 5 is a series of details of the prismatic-glass tiles in connection with which I have illustrated my invention. Fig. 6 is an end view of the table and arrangements. Fig. 7 is a plan view of the follower-plate. Fig. 8 is a cross-section of a portion of the same. Fig. 9 is a detail of strip-securing device. Fig. 10 is a cross-section through a portion of the device.

Like parts are indicated by the same letters in all of the figures.

A is the table upon which the work is to be done. This table is preferably supported by the trunnions B B on the standards C.

D is a follower-plate having the ribs E E and the margin F, the ribs being in this case adapted to be received within the slots E' E', formed between the prismatic ribs on the glass when the sheet has been set up.

G G are clamps whereby the follower may be attached to the table, so that the table can then be turned on the trunnions and the completed work be reversed.

H is a table supported on the legs H' H' in any desired manner and adapted to be put underneath the table A when the latter has been reversed, so as to receive the follower-

plate D with the glass thereon for the second stage in the preparation, as hereinafter referred to.

The table A has fixed about its edge a suitable margin J. This margin is cut out at J' and in like manner from end to end at suitable distances and is so attached to the table that the bottom of the slots J' is in substantially the same plane as the surface of the table A. Along the margin J are pivoted the metal locking devices K, having each the slot K', which does not quite register with the slot J'. Each of these devices has the handle K², whereby it may be conveniently controlled.

The strips L L, which in part form the frame, are received into the two slots J' K', passing therethrough and being clamped therein by reason of the fact that the slots do not quite register, and such strips are then turned over at the ends K³, whereby such ends are securely fastened in the margin-piece J.

M is a movable piece or bar, preferably in the shape of an angle-bar in cross-section and adapted to slide on the frame or table and provided with slots through the upwardly-projecting part of the angle-bar to receive the ends of the strip L, these slots being also enlarged to extend into the lower portion of the angle-bar, so as to receive the upset or overturned ends of the strip L, and thus permit these strips L to rest against the table. The angular slots are indicated by the letter X. In making up the frame a series of these strips L are secured, as indicated, to the margin-piece J, and then their other ends M' are forced into the angular slots, care being taken to have them of proper length and practically all the same length. The glass tiles having preferably been brought to practical uniformity in size and shape are inserted between the strips, a series of them being placed along the strips in proximity to the margin J.

I prefer to place a series of blocks N between the outer tile sections and the margin J, such blocks N being of substantially the same thickness as the marginal portions of the tile. After the first series of tile pieces N' N' are laid in position short metallic strips N² N² are interposed between the strips L L, and another series of parallel tile sections N³ are placed

in line, and so on until a sufficient number of tile sections have been thus set in to complete the glass as desired. Blocks and wedges N^4 N^4 are then inserted between the margin-piece M 5 and the last of the tile sections, and by driving such wedges together the whole frame can be brought up into a secure sheet of tightly-fitting sections and strips. This stretches the strips and tightens and straightens all the 10 parts, but does not make or build a frame; nor are these several parts in any manner at this stage secured to the glass sections. All this work is done with the ridged surfaces of the tile upward, as indicated in Fig. 1.

15 The next process will be best explained by referring to Fig. 3. A series of washers O , preferably stamped metal washers, having each a central aperture, are now laid and set with solder over the angles formed by the 20 strips. I prefer to apply these washers only at such points as indicated in Fig. 3, though they may be applied also around the margin. I now lay along the margins of the glass strips $O' O'$, which thus, as indicated, lie upon the 25 thin margins of the tile and overhang the same a considerable distance. This is shown by the dotted lines in Fig. 3. Each of these strips is preferably provided with an aperture, into which a quantity of solder O^2 may 30 be dropped, so as to thus fix the strip L or N^2 , as the case may be, and the strip O' together, as indicated in Fig. 10. Broadly speaking, the term "washer" would apply to the two methods of attachment which I have described, either that indicated in Fig. 10 or 35 that indicated by O in Fig. 3, and either is interchangeable, and either can be applied in either of the two positions, but I prefer the arrangement indicated and above described. The object, however, is to tentatively complete the frame so as to have the 40 glass held loosely in position, each piece in its proper place. When all this has been done, the follower-plate may be applied as indicated in Fig. 6, thus holding all of the parts 45 in position. The whole may be reversed and the follower be deposited on the table H , the clamps G be loosened, and the table A be removed, thus leaving the glass sections with 50 their flat sides upturned, as indicated in Fig. 2.

To free the partially-finished glass plate from the table on which it is first formed, as above described, it will be necessary, of course, to cut the strips at the proper time and in any suitable manner. These strips L will of course be cut or severed as nearly as may be convenient to the edges of the outer sections of glass or prism lights by 55 means of shears or otherwise. I now place and set the strips and washers similar to those described in Fig. 3 on the plate, thus tentatively finishing the frame. The plate can then be handled if care be taken, the following-plate being first tipped into nearly a vertical position and the compound plate of glass being carefully handled in slings or

loops, the ends of the strips O' being first cut on the dotted lines, as indicated in Fig. 2. Each edge of the plate is then dipped 70 in paraffin, for example, so as to form between the strips $O' O'$ and about the margin of the compound glass plate a body of paraffin P . The outer edge of this paraffin can then be coated, for example, with plumbago, 75 as indicated at P' , whereupon the whole plate is ready to be subjected to the action of the electrolytic bath. The effect of this bath will be to form a coating R about the strips O' and the plumbago and paraffin $P' P$, thus 80 forming a complete sealed metallic margin about the finished compound plate. This action at the same time, however, forms a sealing and securing deposit between the preferably-roughened margin edges S of the sections of prismatic glass and the opposed edges 85 of the strips L and N^2 . This action also sets all the washers and securely fixes them in position. This process, if continued long enough, and it may be, if desired, will also 90 form an overhanging ridge or ledge along the margins of the metal strips, as indicated at $T T$, Fig. 5, thus further completing the frame and holding the glass securely in position. When these several processes have been completed, it will be found that the result is a 95 strong, stiff, firm, weatherproof compound sheet of glass. It will also be found that in no other preparation of this kind has there been such narrow or almost imperceptible 100 opaque lines of separation between the several sections of glass.

I have spoken of cutting the strips off. It is better to cut them off leaving a certain amount of length, so that they can be bent 105 over, and their bent-down ends will thus lie between the marginal strips and within the groove formed thereby. The fastening devices, in one instance being a washer and in the other the mass of solder, are arranged so 110 as to overhang the glass or the marginal strip and be secured to the framing-strips.

If, as indicated in Fig. 3, the prisms are nearly as long as the body of the glass, then the deposited metal will flow into the angles 115 between such prisms and hold the parts in position.

I have spoken of framing-strips. Of course I mean to include anything which would serve the purpose, and I have even used wires, about 120 which the metal will build up. The short strips I prefer to use, but they might of course be made longer and the two intersecting strips be notched; but such strips would be less easily used in my present method of operation. 125

The edges of the sections are commonly beveled, as indicated in the upper view of Fig. 5, and when ground off to be vertical the grinding is preferably done with such a stone and in such a manner as to leave the edge roughened, as indicated. The exact effect cannot well be produced in the drawings, but will be easily understood. This tends to hold the metal when the electrodeposition takes place. 130

I have spoken of dipping the edge, so as to fill the groove between the marginal strips, in paraffin; but of course I mean to reserve the right to use any sort of proper filling substance. Paraffin seems at the present time to be satisfactory.

I claim as new, and desire to secure by Letters Patent, the following:

1. A prism-plate comprising the following elements: a series of sections of glass or prism lights, metallic framing-strips between their opposed edges, overhanging metallic strips secured about the exterior edges of the marginal sections or prism-lights, so as to form a sort of marginal groove, a filling substance in such marginal groove, provided with a conducting-surface and electrodeposited metal about all the strips and the filling substance and between the interposed strips and the edges of the glass sections.

2. A prism-plate comprising the following elements: a series of sections of glass or prism lights, metallic framing-strips between their opposed edges, overhanging metallic strips secured about the exterior edges of the marginal sections of glass or prism lights, so as to form a sort of marginal groove, a filling substance in such marginal groove provided with a conducting-surface, electrodeposited metal about the overhanging strips and the filling substance and between the interposed strips and the edges of the glass sections, and overhanging ledges of deposited metal on the framing-strips, so as to form each of them into a sort of I-beam.

3. A prism-plate comprising the following elements: a series of sections of glass or prism

lights, metallic framing-strips between their opposed edges, overhanging metallic strips about the exterior edges of the marginal sections of glass or prism lights, so as to form a sort of marginal groove, a filling substance in such marginal groove, provided with a conducting-surface connecting devices at the corners of the sections, which overhang such corners and are secured to the framing-strips, and electrodeposited metal about all the strips and the filling substance and between the interposed strips and the edges of the glass sections.

4. A prism-plate comprising the following elements: a series of sections of glass or prism lights, metallic framing-strips between their opposed edges, overhanging metallic strips secured about the exterior edges of the marginal sections of glass or prism lights, so as to form a sort of marginal groove, a filling substance in such marginal groove provided with a conducting-surface connecting devices at the corners of the sections which overhang such corners and are secured to the framing-strips, electrodeposited metal about the overhanging strips and the filling substance and between the interposed strips and the edges of the glass sections, and overhanging ledges of deposited metal on the framing-strips, so as to form each of them into a sort of I-beam, and electrically-deposited metal about such connecting devices.
